UNITED STATES PATENT OFFICE.

FRANK OBERST, OF GLENDALE, NEW YORK, ASSIGNOR TO SONORA PHONOGRAPH CORPORATION, A CORPORATION OF NEW YORK.

AUTOMATIC STOP.

1,392,077.

Specification of Letters Patent. Patented Sept. 27, 1921.

Application filed July 2, 1919. Serial No. 308,131.

To all whom it may concern:

Be it known that I, FRANK OBERST, a subject of the Kingdom of Roumania, and residing at Glendale, in the borough of 5 Queens, county of Queens, and State of New York, have invented certain new and useful Improvements in Automatic Stops, of which the following is a specification.

My invention relates to an automatic 10 stop device for talking machines, and has for its objects to produce such a device which will be operated by means actuated by the movement of the stylus as the latter travels across the record disk by the 15 engagement of the stylus with the record groove, and which will automatically operate mechanism to cause a brake to be applied to a moving element to arrest the rotation of the motor mechanism of the table 20 machine.

A further object is to provide a device of the character described and by means of which the brake may be manually applied or manually released from engagement with 25 the turn-table.

A further object of the invention is the provision of an automatic stop of the character described, simple in construction, neat and attractive in appearance, thoroughly reliable and efficient in its purpose, and economical to manufacture, and which will not 30 get out of order.

With these and other objects in view to be more fully set forth hereinafter, the 35 invention consists in the novel construction, combination of elements, and arrangement of parts which will be exemplified in the construction hereinafter described in the specification and illustrated in the accompanying drawings considered together or 40 separately.

The invention will be first described in connection with the accompanying drawings, illustrating one embodiment of my invention, wherein similar reference characters 45 are used to designate corresponding parts throughout the several views, and then more specifically defined and indicated in the appended claims.

50 In the drawings,

Figure 1 is a plan view of the device, the turn-table being shown in dotted lines, and

Fig. 2 is a side elevation partly in section.

55 In carrying out my invention, I provide

a base plate 1 which is secured to the motor board 2 of a talking machine, and at one side of axis of the turn-table.

Pivoted to the base plate is a handle lever 3 and pivoted at 4 to the handle 3 is one 60 end of a pitman 5. The opposite end of the pitman is provided with a slot 6 through which projects a screw 7. The extremity of the pitman is provided with a nose 8 and an 65 extension 9.

The nose 8 is adapted to engage a cam face 10 on a lever 11 pivoted at 12 to the base plate. One end of the lever 11 carries a pawl 13 adapted to engage a ratchet tooth 14 on a brake lever 15 pivoted on the screw 70 7. The lever 15 carries a brake shoe 16 adapted to engage the inner periphery of the flange 17 of the turn-table 18. A spring 19 is secured to the brake lever 15 and to the lever 11. The base plate carries a stop 75 20 to limit the movement of the lever 11 in one direction.

At the end opposite the pawl 13 the lever 11 carries a pin 21 adapted to be engaged by an element 22 carried by the tone-arm 80 (not shown) of the talking machine.

Rotatably mounted on the pivot 23 of the handle lever 3 is a detent 24 the head of which is held in engagement with a notch 25 in the pitman 5 by means of a spring 26. 85 The detent 24 acts to prevent overthrow of the pitman.

When the parts are in the position shown in full lines in Fig. 1, the brake is released and the turn-table is free to rotate under 90 the influence of the spring of the motor (not shown). The brake arm is locked with the shoe 16 out of engagement with the flange 17 of the turn-table, by the engagement of the pawl 13 with the tooth 14. 95

As the stylus of the sound-box reaches the inner end of the record groove the element 22 which may be carried by the tone-arm comes into engagement with the pin 21 and actuates the lever 11 to release the pawl 100 13 from the tooth 14 and the spring 19 will apply the brake shoe 16 to the flange of the turn-table and arrest the rotation thereof. The pitman 5 is not affected by this movement and the handle lever 3 remains in the 105 position shown in full lines.

When the tone-arm is swung back over the record to engage the beginning of a new record groove, the lever 3 is swung to the right as shown by the dash and double dot 110

- line. This movement will pull the pitman downward and the extension 9 of the nose 8 will engage the upper edge of the brake lever 15 and move the same to the full line 5 position when the pawl 13 will engage beneath the tooth 14 and lock the shoe 16 in the position away from the turn-table.
- If, when the brake shoe is locked out of its operative position, it is desired to apply 10 the brake before the stylus reaches the end of the record groove, the handle 3 is swung to the left as shown by the dot and dash lines. The pitman 5 will be raised, or moved in the direction away from the lever 15 3, the lever 11 will be actuated by the engagement of the extension nose 8 with the cam face 10, the pawl 13 will be disengaged from the tooth 14 and the brake will be applied.
- 15 20 In accordance with the provisions of the patent statute, I have described the principle of my invention, together with the apparatus which I now consider to represent the best embodiment thereof, but I desire it 25 understood that my invention is not limited to the particular form of apparatus herein shown and described, as it is obvious that the particular embodiment herein shown and described is only illustrative of my invention, and that other means can be employed to obtain these objects and accomplish these results, without departing from the spirit of my invention.

Having now described my invention, what 35 I claim and desire to secure by Letters Patent is:

1. A device of the character described, comprising a pivoted brake beam, a pivoted lever engaging the brake beam for holding 40 the brake in released or off position, and a pivotally mounted member for moving said lever to inoperative position to permit the brake to be applied, the pivots of the brake beam, the lever and member all being substantially in the same straight line.
2. A device of the character described, comprising a pivoted brake beam, a tooth on the beam, a pawl engaging the tooth, a 45 spring adapted to move the beam in one direction, a manually operated slide for mov-

ing the beam in the opposite direction, and positively acting means for preventing overthrow of the slide.

3. A device of the character described, comprising a pivoted brake beam, a tooth on 55 the beam, a pawl engaging the tooth, a spring adapted to move the beam in one direction, a manually operated slide for moving the beam in the opposite direction, and a spring pressed finger for preventing the 60 overthrow of the slide.

4. A device of the character described, comprising a pivoted brake beam, a tooth on the beam, a lever pivoted intermediate 65 its ends, a pawl on one end of the lever for engagement with the tooth, a cam on the lever, a pitman mounted for movement in a direction through the pivot of the lever, a lever for moving the pitman whereby the pitman will engage the cam to release the 70 pawl from the tooth, and a spring connecting the beam and lever.

5. A device of the character described, comprising a pivoted brake beam, a tooth on 75 the beam, a pivoted lever, a pawl on the lever for engagement with the tooth, a cam on the lever, a pitman, a lever for moving the pitman into engagement with the cam in the direction of the length of the lever whereby the pitman will engage the cam 80 to release the pawl from the tooth, and a spring connecting the beam and lever, and means carried by the pitman for moving the brake beam against the tension of the spring.

6. A device of the character described, comprising a pivoted brake beam, a tooth on the beam, a pivoted lever, a pawl on the lever for engagement with the tooth, a cam on the lever, a pitman, a lever engaging the 90 pitman for moving it, whereby the pitman will engage the cam to release the pawl from the tooth, means engaging the pitman at a point spaced from its engagement by the lever for retarding the movements of 95 the pitman, and a spring connecting the beam and lever.

This specification signed this 27th day of June, 1919.

FRANK OBERST.
